SPECIFICATION forming part of Design No. 13,156, dated August 8, 1882.

Application filed June 30, 1882. Term of patent 3½ years.

To all whom it may concern:

Be it known that I, EDUARD LEISSNER, of New York, in the county and State of New York, have invented a new and original Design for Wall-Paper and Similar Fabrics, of which the following is a specification.

This invention relates to a new and original design for wall-paper and similar fabrics; and it consists in the novel grouping and configuration of parts hereinafter more fully described.

The accompanying photograph illustrates a face view of a wall-paper having my new design.

A is a vine bearing upon it leaves and tulip-like flowers. B is another vine, which forms a loop around the vine A, and which bears upon it the large conventional flower-like or leaf-like figure a, which resembles a serrated leaf; also, the figure b, resembling a flower with deeply-cut petals; also, the figure c, resembling a leaf; also, the figure e, a somewhat similar leaf, and g a flower similar to b, and f a projecting fan-shaped flower. These two vines, interlacing with each other and with their projecting leaves, flowers, and buds, form the design. 20 25
